UNITED STATES PATENT OFFICE.

THOMAS JOHNSON, OF ST. LOUIS, MISSOURI.

GASOLINE-VAPOR BURNER.

SPECIFICATION forming part of Letters Patent No. 292,032, dated February 5, 1884.

Application filed August 9, 1883. (No model.)

To all whom it may concern:

Be it known that I, THOMAS JOHNSON, of the city of St. Louis, in the State of Missouri, have invented a certain new and useful Improvement in Gasoline-Vapor Burners, of which the following is a specification.

Figure 1 is a side elevation of my improved burner-head connected to a tank by a suitable supply-pipe. Fig. 2 is a vertical section of the burner-head on the line 2 2, Fig. 3. Fig. 3 is a top view thereof. Fig. 4 is a horizontal section on the line 4 4, Fig. 1.

A is a tank; B, the supply-pipe, which may have a valve, B', and C the vertical hollow stem having valve-rod H, and through which the supply-pipe is connected to the burners.

G is a head-block formed with valve-seat *g* at bottom, vertical passage *g**, leading therefrom, radial passages *g*', hollow screw-threaded 20 projections *g***, forming extensions to the radial passages, and means by which the supports for the caps and jets can be secured removably to the head-block, and, lastly, with a neck, *g****, by which the head-block is coupled to the stem.

D are the supports for the caps and jets, *d* being the caps and E the jets. The jets are L-shaped, the vertical portion being screw-threaded to fit in passages *d*'' in the supports. 30 These passages *d*'' are threaded to receive the jets at their lower ends, and at their inner ends are threaded to fit the projections on the head-block to secure the supports to the latter. The supports have central openings, *d*', under which the jet-arm extends, as usual.

Beneath the jets a tray or plate is supported on the stem, and is formed with a number of oil-cups, one for each jet. The valve-rod passes down through a stuffing-box, I, on the lower end of the hollow stem. The lower end 40 of the valve-rod is provided with a suitable lever, J, by which it is turned.

The valve-rod may be supported near its seat by a guide, *c*, so that it will always find its seat, and, as the point of bearing between 45 the rod and stem is at their lower extremities, there is no danger of them becoming fast, so that the former cannot be easily turned when heated by the burners.

Having thus described my invention, the 50 following is what I claim as new therein and desire to secure by Letters Patent:

In a gasoline-vapor-burner head, the combination of the head-block G, formed with valve-seat *g* at bottom, neck *g***, vertical passage *g**, radial passages *g*', hollow threaded 55 projections *g***, forming extensions to the radial passages, the supports D, secured to the projections and having central openings, *d*', and passages *d*'', in communication with the radial 60 passages, extensions, and the L-shaped jets E, secured in the passages in the supports, as set forth.

THOS. JOHNSON.

In presence of—

SAML. KNIGHT,
GEO. H. KNIGHT.
